UNITED STATES PATENT OFFICE.

JOHN P. BALL, OF CHICAGO, ILLINOIS.

MARINE WALL CONSTRUCTION.

Application filed November 28, 1924. Serial No. 752,669.

My invention relates to marine walls consisting of a timber or pile foundation; the object of the invention being to provide such walls with a concrete cap or coping; that is to say, my invention consists in providing the upper ends of the timbers, or the tops of the piles, with a concrete cap, the top whereof extends above the surface of the water, while the bottom of the coping 5 is disposed beneath the surface of normal level of the water my improved construction being adaptable for jetties, wharves, piers, revetments, foundations, bulk-heads and the like.

One object of the invention is to provide pre-cast hollow concrete sections or cribs intended to be placed end to end; each section or crib consisting of separately formed or pre-cast sides hingedly or yieldingly 20 linked together at a suitable point intermediate of the top and the bottom of the sides, with each side being provided with a bottom forming leg or portion adapted to abut against the adjacent side of the timber or pile foundation beneath the top thereof; that is to say, the positioned sections and completed coping will grip the timber or pile foundation at a point beneath the surface of the water and therefore encase or 25 house the exposed portion of the foundation or piles where decay takes place.

The objects and advantages of my invention will all be more fully comprehended from the detailed description of the accompanying drawing, which forms a part of my specification, and wherein:—

Figure 1 is a sectional perspective view of a portion of my improved marine wall construction, partially filled in with mass concrete; the exposed upper ends of the piling and the exposed ends of the waling strips at the end of the wall construction being shown in elevation (the other piles and remainder of the waling strips being embedded 40 in the concrete and therefore invisible) with portions of the foundation and mass concrete filling being broken away.

Figure 2 is a plan view of a portion of my improved wall construction with the mass concrete in the coping units and between the two rows of piles and coping omitted as well as the precast slab covering the mass concrete between the two rows being omitted.

Figure 3 is a vertical section of a modi-

fication, disclosing a hollow crib or cap 55 shown applied to the upper end of a pile and provided with mass concrete filling.

Figure 4 is a transverse section of the modified form of my improved concrete crib as applied to a single pile as shown in Figure 3, and filled in with mass concrete.

My invention consists more especially in providing a suitable cap or coping, of pre-cast concrete, for the upper ends of the piles and for the waling strips of breakwaters, bulk-heads piers and the like, whether immediately or subsequently applied thereto.

In the exemplification of the invention as disclosed in Figures 1 and 2, a portion 70 of the foundation of a bulk-head or pier is shown at 5. These foundations usually consist of ordinary rock filling employed in conjunction with the piles of the bulk-heads; the piles being usually braced with waling strips and tie-rods intermediate of the facings or sides of the bulk-head or crib. The bulkheads usually consist of rows of piles arranged in suitable spaced relation, with the upper ends of the piles terminating or 80 cut away to approximately normal water level, or slightly above the water surface or level as shown. The piles, after being driven to a definite grade, are usually sawed off at the top to a desired extent after the 85 piles have been provided with and bound together by suitable waling strips either wood or metal, which are suitably secured to the respective piles by means of bolts and tie rods; the tie rods extending from one row 90 of piling to the other.

Where my invention is intended to be applied to a previously constructed bulk-head or pier, a portion of the top stone of the foundation intermediate of the two rows 95 of piling, is first removed to permit the application of my precast hollow crib or coping.

My improved hollow crib or coping 6 comprises precast concrete units arranged 100 in pairs; each unit consisting of a side wall portion 7 having an angularly disposed bottom forming portion 8. The units are cast to a predetermined size and dimension to suit the particular type of piling and construction employed. The two units constituting a crib, form one portion or section of 105 a continuous coping, as disclosed in Figures

- 1 and 2 and the units of each crib are substantially identical in construction and configuration. These units are intended to be placed on opposite sides of the same row of 5 piling with the bottom portions 8 arranged in abutting relation with opposite sides of the piling 9 as shown very clearly in Figure 1; that is to say the bottom portions 8 of each unit engage with the piling at a suitable 10 point beneath the waling strips 10. Each unit is preferably formed of reenforced concrete; the reenforcement, at least in certain portions thereof, comprising suitable metallic rods, which extend from the bottom portions 15 8 and are disposed vertically throughout the sides 7; and these rods, or at least some of them, are preferably bent upon themselves to form a loop or eye-portion 11 which extends or protrudes through the inner side or face of the side wall portion of 20 the units. The loops or eye-portions are preferably arranged at a point slightly beneath the horizontal axis or centers of the side portions of the unit.
- 25 The units, namely the two portions 6, constituting the crib or coping section, are put into position, after the foundation has been properly prepared therefor, by having the bottom portions 8 of each unit brought into 30 abutting relation with opposite sides of the piles 9 at a point beneath the waling strip 10. The units after being positioned as just described are then secured together by means of suitable hook-bolts 12 which engage 35 with the loops or eyes of the reenforcing rods in the two units of the crib or coping. It will be understood, of course, that instead of employing a bolt, as just stated, any suitable tie means may be used.
- 40 After the units of the crib or coping have all been put into position as described, the coping is then preferably filled in with mass concrete, which may be reenforced if desired; the concrete being poured in through 45 the open top of the crib or coping (the ends and joints being suitably sealed beforehand) and caused to completely fill the crib on all sides of the piles as well as beneath the waling strip in order to thoroughly 50 encase the tops of the piles and waling strip as well as the tie means or bolts which engage with the loops or eyes of the reenforcing rods previously described and the ends of the tie-rods which are secured to the 55 piles or waling strips, so as to provide a homogenous structure therewith which completely encases the wood structure of the bulk-head or pier and provides a continuous beam.
- 60 It is apparent that by having the yielding or hingedly connected tie means 12 disposed transversely beneath the horizontal axis or center of the sides of the crib that the bulk 65 of the mass concrete or filler 17 introduced will be above the tie means so that the ex-

pansion will force the upper ends or top of the cribbing in an outward direction, thereby ensuring the bottom portions of both units to come into firm abutting relation with and to grip the piles; the filler 17 or 70 concrete being disposed in the crevices between the piles and beneath the waling strips as well as around the tie-rods or fastening elements and as a result cause the crib or coping to be firmly gripped in place. 75

It is usual in the construction of bulk-heads and piers of this character, namely where double rows of piling are used in horizontal spaced relation, to secure the front and rear rows of piling together by 80 means of tie-rods 14 which are arranged at predetermined spaced relation; the tie-rods 14 extending through the waling strip 10 secured to one row of piling—the end of the tie-rod being provided with a suitable 85 washer and nut as shown at 15 in Figure 1—and through the waling strip of the other row of piling, with the outer end of the tie-rod at the last mentioned end being disposed through a metallic channel bar shown 90 at 16 in Figure 1. As the tie-rods are usually more or less uniformly spaced apart as previously stated, I prefer to make my precast concrete units of a size adapted to fit intermediate of the adjacent tie-rods as 95 shown in Figure 2. That is to say, the ends of the respective units or cribs are adapted to come into close relation with the sides of the tie-rods 14. After the units have been placed as described, the crevices or joints 17 intermediate of the longitudinally disposed units or cribs may then be sealed and filled in with cement or concrete in any suitable manner so as to completely seal all crevices 100 17 and prevent the ingress of water. 105

After the cribbing or coping for both the front and rear rows of piling has been positioned as previously described, the space intermediate of the front and rear rows is then filled in with quarry-run stone as indicated at 19 in Figure 1; the filling 19 being arranged on the foundation 5 and preferably to a point slightly beneath the tops of the cribbing or coping so as to permit the placing of a cover of reenforced concrete in 110 the nature of a slab as shown at 20; the reenforced concrete slab 20 at the same time acting as a reinforcement for the bulk-head. The covering or slab is preferably arranged flush with the tops of the cribs or coping 115 and may be secured thereto by means of reenforcing rods as shown at 21.

In Figures 3 and 4, I show a modification of my invention which consists in providing a separate cap for each pile; the cap or coping in this instance being composed of substantially semi-cylindrical units 22 which are substantially identical in configuration. These units 22, like units 6, are formed of reenforced concrete, having a 120 130

bottom portion 23 which at its outer perimeter is given a curvature to fit about the pile 9, as clearly shown in dotted lines in Figure 3. Each unit or side of this crib 5 or coping, like that shown in Figures 1 and 2, is provided with a reenforcing rod extending laterally in the bottom portion and vertically throughout the side wall thereof. The reenforcing rods, at a point 10 preferably beneath the horizontal axis or center of the side walls are bent into loop or eye form as shown; with the loop or eye-portion disposed through to the inner side of the crib or coping as shown at 24; 15 these loops or eyes being disposed in a plane above the top of the pile. The two side walls or units are then secured or tied together by a suitable bolt or tie means indicated at 25, which may be of the same nature 20 as that previously described in connection with the construction shown in Figure 1. After the units of the coping shown in Figure 3 have been put into place about the upper end of the pile, the upper ends or 25 tops of the units are preferably held in proper spaced relation, in preparation for the filler or concrete, in any suitable manner as for example by a strut timber or member indicated in dotted lines at 26. The 30 coping is then filled in with suitable concrete which is poured so as to completely encase the top of the pile and the loops or eyes 24, as well as tie means 25; suitable means having been employed to close the 35 crevices intermediate of the two units or halves of the coping while the concrete is being poured.

It is apparent that by the use of this invention, the tops of the piles will be completely encased in concrete, the outer shell or portion whereof consists of precast concrete units which have been previously matured before contact with the water where the bulk-head or pier is being constructed 45 and as a result a more desirable and lasting coping is provided than is the case where mass concrete is poured so as to be in contact with the water.

As is apparent from the construction 50 shown and described, the invention provides a continuous beam whereby the respective piles of a row are firmly anchored together and the deteriorating action of the elements on the wooden piles and waling strips, whether wood or metal, is prevented as the 55 upper ends of the piles will be completely encased in concrete, the outer surface or shell whereof consists of a precast and therefore thoroughly matured concrete unit or section, which may be placed in deep or shallow water; water-tight housing for the 60 piles being thus provided.

I have illustrated the cribs or coping 65 consisting of units of a certain configuration, but it is apparent that the configuration or

shape as well as other details of construction may be somewhat altered without departing from the spirit of my invention.

What I claim is:

1. In a marine wall construction involving 70 piling, complementary precast reenforced concrete units, each consisting of a bottom and one side wall, the units being disposed on opposite sides of the piling with their bottoms arranged in abutting relation with 75 opposite sides of said piling, and means intermediate of the side walls of the two units and disposed transversely of the piling whereby the complementary units are yieldingly secured together. 80
2. In a marine wall construction, a pair of complementary precast, reenforced concrete units, each comprising an integral bottom and vertically disposed side portion, and tie-means intermediate of the opposing 85 surfaces of the side portions of both units, with said tie-means arranged at a point intermediate of the tops and bottoms of the units and beneath the horizontal axis of said side portions. 90
3. In a marine wall construction, a pair of complementary precast reenforced concrete units, each comprising an integral bottom and side portion, a rod embedded in the 95 bottom and side portion of each unit, said rods being bent intermediate of their ends into loop form, with said bent portions disposed outward through the side portions on the inner sides thereof, and means engaging with the bent portions whereby the complementary units are yieldingly held together. 100
4. In a marine wall construction consisting of piles, a coping for the upper ends of the piles comprising precast complementary reenforced units adapted to be arranged on opposite sides of the piles and each having a horizontally disposed bottom portion and a side wall portion, the bottom portions of the two units being arranged in abutting relation with opposite sides of the piles, tie means whereby the units on opposite sides of the piles are yieldingly secured together, the channel formed by the complementary units being filled in with mass concrete from bottom to top so as to embed the upper ends 105 of the piles and the tie means and causing the bottoms of the units to move toward the piles. 110
5. In a marine wall construction, a pile cap or coping consisting of a pair of precast, reenforced concrete units, each having a horizontally disposed bottom forming portion and an upstanding side, the perimeter of the bottom portion being made to conform substantially with the side of the pile, tie-means whereby the units are secured about the pile, and a concrete filling for the coping whereby the upper end of the pile and the tie-means are embedded. 115
6. A marine wall construction, consisting 120
- 125
- 130

- 4
- of piles arranged in spaced rows, the piles of each row being braced by waling strips and the two rows secured together by tie rods, coping for the piles comprising precast concrete complementary units each consisting of a side wall and bottom forming portion, a unit being arranged on each side of the piles, tie means secured to the sides of the two units at a point between the top and bottom of the sides, a filling of concrete in said coping, and a concrete slab disposed intermediate of the coping of both rows or piles.
  - 7. In a marine wall construction consisting of piles, a coping for the upper ends of the piles, comprising precast complementary

concrete units arranged on opposite sides of the piles, each having a horizontally disposed bottom portion and a vertically disposed side portion, the bottom portions of the units being arranged in abutting relation with the piles, reinforcing rods embedded in the units with intermediate portions of said rods formed into loop form and extending through on the inner surface of the side wall of each unit at a point nearer to the bottom than to the top of the unit, and tie means connected with the loops of both units, the coping being adapted to be filled with mass concrete embedding the tie means and the upper end of each pile.

JOHN P. BALL.
